UNITED STATES PATENT OFFICE.

THOMAS F. CASEY, OF NEW YORK, N. Y., ASSIGNOR OF ONE-HALF TO OSCAR HORSTMAN, OF NEW YORK, N. Y.

CONTROL APPARATUS FOR FUEL-SUPPLY FOR INTERNAL-COMBUSTION ENGINES.

1,208,480.

Specification of Letters Patent. Patented Dec. 12, 1916.

Application filed January 26, 1916. Serial No. 74,423.

To all whom it may concern:

Be it known that I, THOMAS F. CASEY, a citizen of the United States, and a resident of the city of New York, borough of Manhattan, in the county and State of New York, have invented a new and Improved Control Apparatus for Fuel-Supply for Internal-Combustion Engines, of which the following is a full, clear, and exact description.

10 Among the principal objects which the present invention has in view are: to prevent an unauthorized supply of fuel to an internal combustion engine; to provide a combination lock for controlling the flow of fuel to an internal combustion engine; to provide an audible alarm actuated by said lock when tampered with; and to provide a poly-membered means for determining the supply 15 of explosive fuel to internal combustion engines, said members being disguised in arrangement.

20 Drawings.—Figure 1 is an assembly of a gasoline tank, carbureter and manifold therefor; a gas supply pipe connecting said gasoline tank and carbureter, and an apparatus for controlling the flow through said pipe, said apparatus being constructed and arranged in accordance with the present invention; Fig. 2 is an assembly showing contact ends of the members of said apparatus when arranged in correspondence with the position shown in Fig. 1 of the drawings, an audible alarm, an electric source operating the same, and a controlling switch therefor; Fig. 3 is a top plan view of the controlling apparatus herein described, partly in section to show the free-way channel with which the apparatus is provided and the controlling plugs therefor; Fig. 4 is a vertical section, the section being taken as on the line 4—4 in Fig. 3.

25 Description.—As seen in the drawings, a supply pipe 9 is operatively connected with a gasoline tank 10 and a carbureter 11, all of conventional form and construction. The pipe 9 is formed in two sections when employing an apparatus constructed in accordance with the present invention, and the 30 ends of said sections are connected to the apparatus by unions 12. As seen best in Fig. 3 of the drawings, the apparatus has a solid bar-like body portion 13, through which a channel 14 is formed. Intersecting 35 the channel 14 are a series of bores, each pro-

vided to receive a plug valve 15. The valves 15 have each a passage formed therein for registry with the channel 14. Each valve 15 has a key extension 16, and each extension 16 has a wrench head 17. The head 17 is preferably shaped to form a square abutment 18 and a flat surface adjoining the same.

The shape of the key heads may be varied. It is preferred, however, that the shape with which they are supplied, should be such as to indicate or suggest a straight line or normal relation. In the normal position, or what might be termed, the suggested normal position of the valves 15, the heads 17 would be so turned that the flat surfaces thereof would be in line, as are the heads in the valves at stations numbered "1", "3", "5" and "7" in Fig. 3. When the valves at stations numbered "2", "4" and "6" are turned so that their heads coincide with the heads of the other valves, it will be seen that the ports in the said valves "2", "4" and "6" are perpendicular to the channel 14, and block the same.

30 The owner employing this apparatus to safeguard his machine, knows the combination, and when he leaves the machine he turns the valves at the stations "2", "4" and "6," if such is the combination, so that the heads are alined. If a meddler or thief 35 desires to operate the machine, it is necessary for him to turn one of the plugs located at the seven stations, and not knowing the combination, he is liable to turn one of the plugs at the stations "1", "3", "5" and 40 "7," which would turn the ports in those valves crosswise of the channel 14, and so 45 block the flow of gas through the pipe 9.

50 It will be understood that the valves 15 may be variously arranged, and the combinations may be altered, so that rarely, if ever, two machines would have the same arrangement or combination.

55 The machine which is equipped with the herein-described apparatus, is likewise furnished with a switch 23 secretly disposed.

In the normal operation of the apparatus, the owner on leaving the machine, closes the switch. Thereafter, if the valves at the stations "2", "4" and "6" be turned, which 60 would open communication through the sections of the pipe 9, the contacts 21 would wipe on the bars 22 and complete the electric circuit incorporating the wire 24, bell 19, battery 20 and common return wire 25. 65 70 75 80 85 90 95 100 105 110

If the thief should not know the combination and should turn any one of the valves 15 at the stations "1," "3," "5" and "7," the electric contacts 21 connected therewith would complete the electric circuit through the wire 24, switch 23, bell 19, and battery 20, or, if turned in the opposite direction, through the bar 26, wire 27, bell 19, battery 20, and common return wire 25. Again, should the owner of the machine be careless and leave the machine with the switch 23 disposed in open position, as seen best in Fig. 2 of the drawings, the thief runs a further chance of turning the valves 15 at the stations "2," "4" and "6," in the wrong direction when the contacts 21 thereof would engage the bar 26. The bar 26 and wire 27 connected therewith are at all times in what may be termed a closed circuit condition ready to operate the alarm bell 19.

Claims:

1. An apparatus as characterized comprising an elongated channel member; a series of plugs disposed transverse the channel of said member, each of said plugs having a port therein adapted for registry with said channel, and each of said ports being provided with a wrench head having an exposed surface indicative of a normal orderly arrangement with reference to the heads of the other plugs, the heads in certain of said plugs having a special arrangement differing from the arrangement of the heads of the other plugs with reference to the ports therein; and an electric alarm system embodying an electric current supply, an audible alarm, and contacts for engaging said plugs when moved from the service position thereof.
2. An apparatus as characterized com-

prising an elongated channel member; a series of plugs disposed transverse the channel of said member, each of said plugs having a port therein adapted for registry with said channel, and each of said ports being provided with a wrench head having an exposed surface indicative of a normal orderly arrangement with reference to the heads of the other plugs, the heads in certain of said plugs having a special arrangement differing from the arrangement of the heads of the other plugs with reference to the ports therein; an electric alarm system embodying an electric current supply; an audible alarm, and contacts for engaging said plugs when moved from the service position thereof; and a manually-controlled switch for said circuit operable for completing the circuit when the plugs are in service relation.

3. An apparatus as characterized comprising a body portion forming part of the gas supply pipe; a plurality of rotary valves operatively mounted on said body portion for closing the passage therethrough; a plurality of laterally extended electrical contacts, one mounted on the stem of each of said valves; a plurality of contact bars disposed at opposite sides of said body portion to engage said contacts when turned to the active position thereof; and an audible alarm incorporated in the electric circuit of which said bars, contacts and body portion form a part.

In testimony whereof I have signed my name to this specification in the presence of two subscribing witnesses.

THOMAS F. CASEY.
